FIG. 5.

FIG. 6.

INVENTOR

GEORGE E. CHAPMAN.

BY Harry J. Sommer

ATTORNEY

UNITED STATES PATENT OFFICE

2,571,011

DEVICE FOR POSITIONING AND IMMOBILIZING INFANTS TO BE X-RAYED

George E. Chapman, Saddle River Township, Bergen County, N. J., assignor to Smith-Chapman, Inc., Irvington, N. J., a corporation of New Jersey

Application September 9, 1950, Serial No. 184,099

11 Claims. (Cl. 250—50)

1

This invention relates to X-ray, fluoroscopic and similar apparatus for photographing and viewing internal body structure. It has been found, in practice, that it is extremely difficult to make X-ray and fluoroscope examinations of infants, particularly those ranging in age from newborns to the age of sitting-up. Such infants are extremely unstable in their body movements and have presented a serious problem to physicians and nurses desiring to take internal radiographic and/or fluoroscopic views of the thymus, chest, skull, spine, abdomen, etc.

The device of this invention is designed to enable the immobilization of such infants for the purpose mentioned in a manner which will materially reduce the amount of time required for positioning an infant, and will substantially simplify the procedure.

These and other advantageous objects, which will appear from the drawings and from the description hereinafter, are accomplished by the structure of my invention, of which an embodiment is illustrated in the drawings. It will be apparent, from a consideration of said drawings and the following description, that the invention may be embodied in other forms suggested thereby, and such other forms as come within the scope of the appended claims are to be considered within the scope and purview of the instant invention.

In the drawings:

Fig. 1 is a perspective view of a device embodying the invention, showing the seat block thereof in dotted lines in the position it would occupy in the use of the device, and in full lines removed from the device but in position for insertion in the supporting plate of the device.

Fig. 2 is a side elevational view of the device shown in Fig. 1, with the seat block shown positioned therein and showing, in dotted lines, the cassette holder of the device in pivoted position relative to the plane of the upright supporting bar of the device.

Fig. 3 is a front elevational view taken on line 3—3 of Fig. 2, and showing, in dotted lines, a lower position to which the seat block may be moved.

Fig. 4 is a fragmentary perspective view, taken on line 4—4 of Fig. 3,

Fig. 5 is a perspective view of the crotch member used in carrying out the invention.

Fig. 6 is an exploded perspective view of a form of seat supporting plate, and a means to engage the same and the bar for positioning the former on the latter relative to the cassette holder,

2

Fig. 7 is a perspective view of a seat block embodying the invention, and

Fig. 8 is an enlarged side elevational view of the seat supporting plate shown positioned on the bar, which is indicated fragmentarily and in dotted lines.

The drawings illustrate a device for positioning and immobilizing infants embodying the invention in a practical form. It will be apparent that variations may be made in view of the disclosure of the drawings and the following description. Such variations and modifications are as comprehended in the scope of the appended claims are to be deemed within the purview of the instant invention.

The device shown in the drawings comprises an elongated upright supporting bar 10 provided with an axial slot 11 and a cassette holder 12 secured to said bar and comprising a bottom wall 13 and side walls 14, 15, and means such as bolts 16, 16' passing through slots 17, 17' in the bottom wall 13 to adjustably secure the side walls thereto. Thus, the side walls may be moved toward and away from each other to accommodate X-ray cassettes of various widths. A seat supporting plate 18 is adapted to be secured to the bar 10 in a position which may be predetermined by the user of the device relative to the cassette holder 12 to accommodate infants of various heights and to position the desired body portion in alignment with the cassette holder. A seat block 19 is provided for the seating of the infant, said block having side walls 20, 21, and end walls 22, 23, and a portion 24 angularly disposed relative to the longitudinal axis of the seat block at one of the end walls thereof. The seat block is provided with means such as keys 25, 25a, 25b, on one or more of the side and end walls and on the angular portion thereof to have complementary engagement with the keyway 26 of the plate 18. The cross sections of the keys and keyways are complementary so as to permit the block 19 to be slid into position on the seat supporting plate. For that purpose, the keys may be of T-shaped cross-section and the keyways of C-shaped cross-section (Figs. 4 and 6). The seat block is provided with an internal opening 30, through which the legs of the infant seated on the block may be positioned. To further assist the positioning of the infant, a crotch member 31 (Figs. 5 and 1) is provided, said crotch member having opposite ends 32, 33, of an outline complementary to the inner faces of the side walls 20, 21 of the block which define the internal opening thereof. By 55 this arrangement, the crotch member may be slid

along the side walls toward or away from an end wall of the block to position the infant at precisely the point desired.

As above noted, the seat supporting plate 18 is adapted to be vertically moved relative to the cassette to thereby fix the position of the seat block on the device; any suitable means engaging the supporting plate 18 and bar 10 may be used to that end. As shown in Fig. 6 (one of many forms useful for the purpose), the supporting plate is provided with a stud 34 fixed at one end to said plate 18 and passing through the slot 11 of the bar 10 and projecting therebeyond. The projecting end 35 of the stud may engage or be engaged by any suitable means to hold the same at the selected position on the bar, as, for example, by providing the stud with threads engaged by the nut member 36 (Figs 6 and 8).

The cassette holder 12 may be rigidly fixed to the bar, or, as shown in Figs. 1, 2 and 4, may be pivotally secured thereto as indicated at 37 (Fig. 2), in which case the cassette holder and bar are provided with means to hold the cassette holder in alignment with the bar, as indicated in Fig. 2 in full lines, or to selectively hold the same in pivoted position at a predetermined angle 38 thereto, as shown in dotted lines in Fig. 2, or at other selected positions. To this end, the cassette holder and bar may be provided with interengaging means for use by the operator, as, for example, the arms 39, 40 fixed to the cassette holder, and a long pin passed through both arms and bearings 43, 44, or short pins 41 passing through slots 42 in the bearings 43, 44 fixed to the bar and through the arms 39, 40, said pins being engaged by nut members 46 or the like to thus fix the position of the cassette holder relative to the plane of the bar 10. This feature of pivotal movement of the cassette holder may be provided for the purpose of enabling an angular disposition of the head, for example, of the patient, where that is desirable for special purposes. The device may be further provided with a flexible band 47 having an end 48 fixed to a side wall, as, for example, wall 15 of the cassette holder by any suitable means, such as the bar 49, and having a free end 50 which may be drawn taut on to the other side wall 14 of the cassette holder, as, for example, by a winding device 51 or the like. The band will hold the part to be X-rayed close to or in contact with the cassette.

From the foregoing, it will be noted that the seat block 19 may be raised or lowered in relation to the cassette holder and may also be positioned at any angle in relation to the cassette holder for posterior, anterior, lateral or oblique views.

The bar 10 may be secured to an X-ray table, wall, floor or other device in any desired or convenient manner.

Having thus described my invention, what I claim as new and desire to secure by Letters Patent is:

1. A device for positioning and immobilizing infants to be X-rayed, comprising an elongated upright supporting bar, a cassette holder secured to said bar, a seat supporting plate, means engaging said plate and bar for adjusted positioning of the plate on the bar and relative to the cassette holder, a seat block for holding the infant, said block having an internal opening defined by side and end walls for the legs of the infant, means on one or more of said end and side walls, for selectively engaging complementary means on said supporting plate to position the seat block thereon, and a crotch member having

ends to slidably engage the side walls of the seat at opposed spaced points to position the crotch member transversely of the longitudinal axis of the seat for slidable movement relative to an end of the seat, to define therewith a constricted leg opening.

2. In a device for positioning and immobilizing infants as set forth in claim 1, said means on one or more of said end and side walls comprising an elongated key fixed thereto, said supporting plate having a keyway therein of complementary cross-section to slidably receive the key.

3. In a device for positioning and immobilizing infants as set forth in claim 1, said means on one or more of said end and side walls and complementary means on said supporting plate comprising an elongated key of T-shaped cross-section and a keyway of C-shaped cross-section to slidably receive the same.

20 4. In a device for positioning and immobilizing infants as set forth in claim 1, said cassette holder being pivotally secured to the upper end of said bar, complementary means on said cassette holder and bar to hold the cassette holder in alignment with said bar or to selectively hold the same in pivoted position at a predetermined angle thereto.

5. In a device for positioning and immobilizing infants as set forth in claim 1, a flexible band having opposite ends, means on said cassette holder to fix one end of the band thereto, and means on said cassette holder engaging the other end of said band to draw the band taut over the infant positioned on said seat.

35 6. In a device for positioning and immobilizing infants as set forth in claim 1, said crotch member having opposed ends of outline complementary to that of the inner faces of the side walls of the seat block.

40 7. In a device for positioning and immobilizing infants as set forth in claim 1, one of the end walls of said seat block having a portion angularly disposed relative to the longitudinal axis thereof and provided with means to engage the complementary means on the supporting plate to position the seat block thereon at a position determined by said angle.

8. In a device for positioning and supporting infants as set forth in claim 1, the means engaging said plate and bar comprising an axial slot provided in the bar, a stud fixed to the plate at one end and having a free end passing through the bar and projecting therebeyond, and means to hold the free end of the stud on the bar at selected position to thereby fix the position of the seat relative to the cassette holder.

9. In a device for positioning and immobilizing infants to be X-rayed, as set forth in claim 1, said cassette holder comprising a bottom and side walls, and means on said bottom and side walls for holding the side walls in selected relatively spaced position to accommodate X-ray cassettes of various sizes.

10. In a device for positioning and immobilizing infants to be X-rayed comprising an elongated upright support bar and a cassette holder secured to said bar, a seat supporting plate secured to said bar, a seat block having side and end walls defining an internal opening for the legs of the infant, and complementary key and keyway means on one or more of said end and side walls and on the supporting plate, to position the seat block thereon at a plane defined by the parallel disposition, with said plate, of the wall of said block engaging said plate.

11. In a device for positioning and immobilizing infants to be X-rayed comprising an elongated upright support bar and a cassette holder secured to said bar, a seat block having side and end walls defining an internal opening for the legs of the infant, and a crotch member having recessed ends to slidably engage the side walls of the seat block at opposed spaced points to position the crotch member transversely of the longitudinal axis of the seat block for slidable movement relative to an end wall thereof to define therewith a constricted leg opening.
